[57] CLAIM

The ornamental design for a catch, as shown and described.

DESCRIPTION

FIG. 1 is a perspective view from above and to one side of a catch showing my design;

FIG. 2 is a perspective view from below and to an opposite side of the catch;

FIG. 3 is a back elevation view of the catch;

FIG. 4 is a front elevation view of the catch;

FIG. 5 is a left side elevation view of the catch;

FIG. 6 is a top plan view of the catch;

FIG. 7 is a bottom plan view of the catch;

FIG. 8 is a perspective view from above and to one side of a second embodiment of the catch showing my design;

FIG. 9 is a perspective view from below and to an opposite side of the second embodiment of the catch;

FIG. 10 is a back elevation view of the second embodiment of the catch;

FIG. 11 is a front elevation view of the second embodiment of the catch;

FIG. 12 is a left side elevation view of the second embodiment of the catch;

FIG. 13 is a top plan view of the second embodiment of the catch; and,

FIG. 14 is a bottom plan view of the second embodiment of the catch.

Each of the catches shown in the attached drawings is symmetric about a vertical plane extending centrally through the front and back of the catch.
